EUGENE HARDESTY, OF NEW BRIGHTON, PENNSYLVANIA, ASSIGNOR TO MAYER CHINA COMPANY, OF BEAVER FALLS, PENNSYLVANIA, A CORPORATION OF PENNSYLVANIA

METHOD OF ORNAMENTING CHINAWARE AND THE LIKE

Application filed January 10, 1931. Serial No. 507,873.

This invention refers to an improved method of applying color to china or pottery ware or the like, to produce a decorated or ornamental effect by the means hereinafter described. The method is particularly applicable to articles, as plates, saucers, dishes, etc., or of any shape of china or glass having a relatively smooth surface. The object in view is the production of an annular band or bands 10 of desired varying light or shade values resulting from the novel treatment involved.

Generally stated, the invention consists in distributing or extending the color from a solid band or line laterally through a fading out or thinner value distribution, with a merging effect from a full color value through a gradually decreasing shade area, fading into the normal background of the ware, as white.

In the drawing, illustrating certain preferred embodiments of the invention:

Fig. 1 is a partial face view of a plate or the like illustrating the applied result of the method;

Fig. 2 is a similar view showing a modification of the treatment;

Fig. 3 is a detail view showing one manner of carrying out the method, by the use of a spreading brush;

Fig. 4 is a similar view showing the use of a sponge or other dauber.

Referring to Fig. 1, the piece of ware 2, as a plate, is first covered, for any desired portion of its annular area, with a solid band 3 of any desirable color. In ordinary well known practice, such color is first ground in a suitable medium as turpentine, and then a "fat" or "slick" oil is added to make the color flow more freely and evenly from the original applying brush. Such operation is preferably performed during rotation or other suitable manipulation of the ware. Numerous such "fat" oils are on the market and are in common use in the industry.

After the color has been thus applied with a brush or the like, forming a band of solid color value of any desired width, another or spreading brush 4, preferably first dipped in turpentine or other similar material, is wiped 50 over the color band, or a portion of it, as by

holding the brush against the ware as it is rotated, as in Fig. 3.

It will be understood also that the same effect may be produced by movement or manipulation of a brush or dauber against a stationary surface, as in the case of non-circular articles not adapted to rotation in a holder.

Dependent on the desired effect, the brush may be held or applied against the ware with slight, increased, or heavy pressure and at varying distances inwardly of the band 3, so that the moist color will be distributed in a fading or decreasing value, as indicated at 5, gradually merging or vanishing into the plain white or other base color surface of the 65 ware.

The same general effect may be secured by using a dauber 4a in the form of a sponge, a ball of cloth, cotton, waste, or the like in the hands of the operator, applied with varying pressure against the surface of the ware and in the same general manner distributing the color throughout the laterally extended varying value margin 5a.

In such application the terminal band 5 will extend from the extreme edge of the ware inwardly in unvarying value, with an inwardly shaded vanishing or fading border. It will of course be understood that the same general effect may be secured at both sides of an original inwardly located band 3 by spreading the color both inwardly and outwardly therefrom, as at 5b on both sides thereof, by proper manipulation of the spreading brush or dauber, as in Fig. 2. The effect may be secured by application at any portion of the ware, and with or without supplemental bands 6 of varying widths or spaces.

It will also be understood that the method may be used with a plurality of different colors, maintaining a solid band of each in annular or parallel relationship with gradual spreading of the color of one toward the other or merging of both, dependent on the desired effect or result and manipulation of the spreading element utilized.

It has heretofore been common to secure a graduated color value effect on chinaware by spraying the color in varying values in

an attempt to secure a fading-out appearance, but such operation results only in a series of more or less closely adjacent spots, without pleasing gradation.

5 However, such treatment may be very greatly improved by subjecting such sprayed color applications to the spreading action of a brush or other dauber, merging the values gradually and continuously throughout the 10 varying lateral extension from the solid band in the same manner as above described.

I have also found that a somewhat similar but slightly different effect may be produced by applying the color as described, then washing it down with a brush dipped in turpentine, and then going over the whole color surface by application of a stiff bristle brush, which however gives a somewhat more streaked effect than that described above. It 15 will be understood that the stiffness of the brush and the degree of pressure with which it is applied will have a varying determining effect on the resulting varying color values, and that such application is entirely 20 within the skill and judgment of the operator to secure continuously similar designs.

After the color has been applied in the manner described, any further decorations 25 may be applied to the ware according to well known methods in common use in the industry, such as additional prints, more lines, or decalcomania or other ornamentation, placed upon or alongside the color application of the present invention.

30 In practicing the invention I have secured excellent results by applying the color to bisque ware with application of the glaze over the color, and such process may be followed 35 equally well on glost ware, or on top of the glaze, or to clay ware before being subjected to the first firing.

Various modifications, developments, and combinations of the above described treatment may be made with varying and pleasing effect, it being understood that fixation 40 of the design is to be secured following the usual firing and other practices in the art. Also, that the method above described is in no way limited to any particular design, or 45 either of the ornamentation or decoration, or 50 of the ware itself.

Having described my invention, what I claim is:

1. In the art of decorating china, glass or 55 similar ware, the method consisting in applying a continuous solid uniform width band of color to the surface and then applying a spreading brush or the like to distribute the edge portion of the band in diminishing color value.

2. In the art of decorating china, glass or 60 similar ware, the method consisting in first applying a color invested with a fat oil in the form of a solid annular band and then 65 spreading a portion of the band by brush

application to extend it in a varying color value margin.

3. In the art of decorating china, glass or 70 similar ware, the method consisting in first applying a color invested with a fat oil in the form of a solid annular band and then spreading a portion of the band by brush application to extend it in a varying and finally vanishing color value margin.

4. In the art of decorating china or similar ware, the method consisting in applying to the neutral surface of the ware prior to glazing an annular band of oil-invested color, then spreading a portion of the band laterally in fading away value extending 80 uniformly beyond the band over the neutral surface of the ware.

5. In the art of decorating china or similar ware, the method consisting in rotating the ware, then applying to the neutral surface thereof prior to glazing an annular band of oil-invested color, and then spreading a portion of the band partially over the neutral surface of the ware in continuous concentric relation to the band and extending 90 therebeyond in diminishing color value.

In testimony whereof I hereunto affix my signature.

EUGENE HARDESTY.
